UNITED STATES PATENT OFFICE.

LEWIS PIRDUN, OF SAND SPRINGS, OKLAHOMA.

HEATING SYSTEM.

Application filed September 17, 1920. Serial No. 410,914.

To all whom it may concern:

Be it known that I, LEWIS PIRDUN, a citizen of the United States, and a resident of Sand Springs, in the county of Tulsa and 5 State of Oklahoma, have invented certain new and useful Improvements in Heating Systems; and I do hereby declare the following to be a full, clear, and exact description of the invention, such as will enable others 10 skilled in the art to which it appertains to make and use the same.

This invention relates to improvements in heating systems, and more particularly to such as employ fluid fuel,—one object of 15 the invention being to provide a simple system in which compressed air may be supplied from a central compressor plant or station for causing liquid fuel to be supplied, properly proportioned with air, through 20 burners to the combustion chambers of furnaces located in buildings in different parts of a town, city or other community, and to so construct features of the system that the supply of fuel and air to the burners shall be 25 automatically controlled according to the temperature of the air or other heating medium within the furnace, thus automatically controlling the temperature of the rooms of a building to which the heated air 30 or other medium is fed from the furnace.

In the accompanying drawing; Figure 1 is a diagrammatical view illustrating my invention; Figure 2 is a view taken at right angles to Figure 1 but omitting the central 35 compressor station; Figure 3 is a sectional view showing a burner which may be employed in my improved system, and Figure 4 is a view, partly in section, illustrating means for automatically controlling supply 40 to the burner.

My invention contemplates a system in which compressed air is supplied from a central station in a town, city or other community, to burners for furnaces in numerous 45 houses in the community for feeding liquid fuel to said burners with the air, but it will suffice for the purpose of this case to show and describe the invention in connection with a single furnace and building as it will 50 be understood that when burners are employed in two or more buildings, it is simply necessary to run branch pipes from the main air line supplied from the central compressor station, to the burners in the various buildings.

1 represents the outline of a building, in

the cellar of which, a furnace 2 is located,—said furnace having a combustion chamber 3 connected in any suitable manner with smoke flue 4, and an air chamber 5, with 60 which one end of a cold air flue 6 communicates. The inlet end of the cold air flue 6 is open and this open end may be located under the porch 7 of the building. The cold air flue may be provided with a branch 8 65 to communicate with one of the rooms 9 of the building, and a damper 10 may be provided at the juncture of the two inlet portions of said flue.

A hot air receiver 11 is located at the top 70 of the furnace structure and communicates with the air chamber 5,—said hot air receiver having connected therewith, hot air flues 12 leading to the various rooms of the building.

Located within the hot air receiver so as to 75 be subjected to the heat units where the same are of maximum degree of temperature, is a tank 13 to which water is supplied by a pipe 14 from any convenient source of supply. This tank is to be kept partially filled with 80 water so that a steam space will be provided above the water level and said tank is provided with a suitable safety valve 15 located near one end thereof which projects outwardly beyond the hot air receiver and beyond the furnace wall.

A burner 16 projects into the combustion chamber 3 of the furnace and is provided with an oil passage 17 and an air passage 18. A tank 19 for liquid fuel may be located outside of the building and, if desired, this tank may be buried in the ground and provided with a capped filling tube 20. A pipe 19^a conveys oil from the tank 19 to the burner.

A compressor plant indicated at 21 and equipped with a suitable air compressor, is located at some convenient central point in a town, city or other community and is connected by suitable underground pipes, such 100 as indicated at 22, with the air passages of burners in the various buildings in which the same are installed.

Each burner is provided with valve mechanisms 23 for controlling the passage of 105 oil and air through the burner and as the two valve mechanisms for each burner may be the same in construction, a description of one will suffice for both. Each valve mechanism comprises a valve 23^a for controlling 110 the inlet of oil (or air) and its stem is connected with one end of a lever 24. This le-

ver is pivotally connected with a standard 25 which projects upwardly from a casing 26 secured to the burner and the chamber of this casing is divided by a flexible dia- 5 phragm 27. A plate 28 rests upon the dia- phragm 27 and from this plate, a stem 29 projects upwardly through the top of the casing 26 and is pivotally connected with the short arm of the lever 24. A spring 10 30 tends to force the long arm of the lever upwardly and normally hold the valve 23^a open. A pipe 31 is connected at one end with the steam space of the water tank 13 and its other end is connected with the dia- 15 phragm chambers of both valve mechanisms, so that the steam pressure will so act upon the diaphragms 27 as to control the oil and air inlet valves.

It will be observed that the compressed 20 air supplied from a central station and passing through the burners will cause a flow of liquid fuel from the tanks 19 to the burners, and said fuel mixing with the air will be projected into the combustion chamber of 25 the furnace, where it will be burned to supply heat to the air within said furnace. The hottest portion of the air within the furnace will be within the hot air receiver 11 from which such air will be 30 conveyed to the rooms of the building. When the temperature within the receiver 11 reaches a high degree and causes the generation of a correspondingly high steam pressure, such pressure acting against the 35 diaphragms of the valve mechanism will partially or wholly close the air and oil inlet valves and thus automatically control the supply of fuel to the furnace according to the degree of temperature reached by the 40 hot air supplied to the rooms of the building.

Branch lines may be taken from the main compressed air lines to convey compressed air to stoves or grates in any desired part 45 of a building for the purpose of cooking or heating, especially when the building is not equipped with a furnace. For cooking and heating with stoves or grates, low grade refined oil or any other liquid fuel may be 50 used with suitable burners, but for furnaces, I prefer to use light fuel oil.

Slight changes might be made in the details of construction of my invention without departing from the spirit thereof or limiting its scope and hence I do not wish 55 to restrict myself to the precise details herein set forth.

Having fully described my invention what I claim as new and desire to secure by Letters Patent, is:—

1. The combination with a furnace having an air chamber, and a hot air receiver at the top of the same and communicating therewith, of a water receptacle in said hot air receiver, a burner entering the combustion chamber of the furnace, a source of liquid fuel supply communicating with said burner, a source of compressed air communicating with said burner, valves for controlling the supply of fuel and compressed 70 air to the burner, pressure operated means for controlling the operation of said valves, and pipe connections between the pressure operated valve controlling means and the steam space of said water receptacle. 75

2. The combination of a furnace having a hot-air receiver, a water-tank in the hot-air receiver of the furnace, a burner arranged to heat the furnace, means for supplying liquid fuel and an atomizing agent 80 to the burner, valves in the passages for said fuel and agent to control the admission of the same to the burner, a casing, a dia- phragm in said casing, a pipe leading from the steam space of the water tank into said casing below the diaphragm therein, levers fulcrumed upon said casing and each connected at one end to one of the said valves and at the opposite end with said dia- phragm, and springs arranged below the res- 85 pective levers at the ends thereof connected with the valves and tending constantly to lift the levers whereby the valves will normally be open. 90

In testimony whereof, I have signed this 95 specification in the presence of two sub- scribing witnesses.

LEWIS PIRDUN.
